UNITED STATES PATENT OFFICE

CHARLES W. GORDON, OF PLEASANTVILLE, NEW YORK, ASSIGNOR TO THE SUPER-HEATER COMPANY, OF NEW YORK, N. Y.

SUPERHEATER ARRANGEMENT

Application filed February 27, 1930. Serial No. 431,783.

My invention relates to arrangements of superheaters in boilers and has as its principal object to provide means whereby changes of position of the boiler with changes in temperature will not harmfully stress a superheater closely associated therewith.

In the ordinary water-tube boiler installation, the boiler is suspended from beams above the roof of the boiler. When a superheater is used, it is often suspended within the boiler intermediate two banks of tubes. When steam is raised in such an installation, the increasing temperature of the boiler parts causes it to sag. The superheater headers, on the other hand, are usually carried on fixed supports and, even if spring supported, can move relatively little in the vertical direction. It is usually necessary that the tube ends between the active or heat absorbing sections of the superheater elements and the headers must pass through internal baffles or outer walls of the boiler. It is undesirable that the combustion gases should pass through such walls, but if the walls and baffles have been made to fit the tube ends closely enough to prevent leakage at the points such ends pass through them, the relative movement of the boiler and superheater parts has damaged the superheater or the boiler wall or baffle.

It is a particular object of my invention to provide means for overcoming the foregoing difficulty.

Two specific arrangements embodying my invention are illustrated in detail in the accompanying drawings. In order that the invention may be clearly and readily understood, a detailed description of the said embodiments will now be given in connection with the accompanying drawings and the features of novelty pointed out in the appended claims. In said drawings,

Fig. 1 is a sectional elevation on the longitudinal plane of a boiler installation having an interdeck superheater and embodying my invention; Fig. 2 is a fragmentary section taken on the line 2—2 of Fig. 1 looking in the direction of the arrows; Fig. 3 is a fragmentary sectional view looking from the right of Fig. 2, one of the vertical tubes of Fig.

2 being omitted and parts being broken away for purposes of illustration; Fig. 4 is a sectional view on the line 4—4 of Fig. 2 looking in the direction of the arrows; Fig. 4a is a detail of a plate shown in Fig. 2; Fig. 5 is a fragmentary sectional view on the line 5—5 of Fig. 6, looking in the direction of the arrows; Fig. 6 is a fragmentary detail elevation of the section of the internal baffle of the boiler shown in Fig. 1 and through which the superheater elements extend; Fig. 7 is a sectional view on the line 7—7 of Fig. 6 looking in the direction of the arrows; and Fig. 8 is an expanded view in perspective of a portion of Fig. 6.

In the arrangement shown in the drawings, 10 indicates in general a boiler of the well-known cross drum, straight tube type having a lower bank of generating tubes 12 and an upper bank of generating tubes 14 spaced apart to provide a chamber 16 for an interdeck superheater 15. In the arrangement shown, superheater 18 has two headers 20 and 22, header 20 lying along one of the outer walls of the boiler and header 22 lying along an inner vertical baffle 24 of the boiler. The tube elements of superheater 18 are shown as supported from the tubes of bank 14 by hangers 26, 26, a known arrangement.

It will be seen that the connecting tube 80 ends between the headers and the active sections of the elements of superheater 18 must pass through the wall 27 covering the water and steam carrying tubes or boiler circulator nipples 28 at one end of the boiler and through the internal baffle wall 24 in order to reach the headers 20 and 22 respectively. It is highly desirable that no leakage of gases occur at the points where the superheater tubes pass through wall 27 and through the baffle 24. However, if an inflexible closure is made at these points, leakage of gas can be prevented only at the expense of stressing the superheater elements and thereby probably causing leakage at the joints between the elements and the headers, or else damaging the outer or inner wall.

In accordance with my invention, I have shown in Figs. 2, 3, 4 and 4a an arrangement for preventing leakage of gases while avoid-

ing stressing of the superheater elements or the wall 27 at the points where the elements pass between the nipples 28. In Figs. 5, 6 and 7 is shown in detail an arrangement in accordance with my invention for accomplishing the same objects at the points where the superheater elements pass through the internal baffle wall 24.

Referring more particularly to Figs. 2, 3, 4 and 4a, 30 and 32 are two tube ends for connecting active sections of the superheater elements with the header 20. It will be evident from Fig. 1 that the tube ends 30 and 32 connect to elements of superheater 18 which lie in parallel vertical planes, but as appears clearly in Fig. 2, the tube ends 30 and 32 are brought one above the other at the points where they pass between the adjacent nipples 28. At such points where the tube ends pass through wall 27, a section of the wall 27 is removed to provide space for installing a flexible non-leaking joint in accordance with my invention. As illustrated, two sets of plates 34, 34a and 36, 36a are provided for each joint and are clamped to opposite faces of a pair of adjacent nipples 28 at points about 120 degrees apart on the surfaces of the nipples. Plates 34, 34a and 36, 36a are beveled as shown at 38, 38, to provide bearing surfaces between the plates and nipples 28 and each pair of plates is drawn together and thereby clamped to a pair of nipples 28 by means of bolts 40, 40 extending from plate 34 to plate 34a and between plate 36 and plate 36a. As shown, the heads of the bolts and the nuts therefor are received into the plates in recesses 41, 41 closed at the back by lugs 42, 42 on the rear faces of the plates so that the nuts and the heads of the bolts need not project beyond the outer surfaces of the plates. The horizontal edge of plate 34 is set close to that of plate 36 so that plates 34 and 36 when in place form in effect one plate. Similarly, plates 34a and 36a lie in the same plane and form, when installed, one plate. Running each way along the vertical edges of plates 34 and 36 from the meeting line between the two, are outstanding flanges 44, 44, one pair on opposite sides of plate 34 and one pair on opposite sides of plate 36. The flanges 44 are bent inwardly as shown at 46, 46 (Fig. 4) to provide grooves 48, 48 for receiving the vertical edges of companion plates 50, 50. Plates 50 run vertically on opposite sides of the tube ends 30 and 32 and are notched to receive such tube ends, plates 50 having outstanding lugs 52, 52 at their centers whereby they may be bolted together and clamped to the tube ends 30 and 32. The plates 34, 34a and 36, 36a are notched out to provide recesses 54, one of which is illustrated in detail in Fig. 4a. When plates 34, 34a, 36 and 36a are clamped together as shown in Figs. 2, 3 and 4, the recesses 54 are made to form an elongated

opening in which the tube ends 30 and 32 may move vertically without striking the edges of the recesses. It will be seen, however, that the opening formed by the recess 54 in the outer plates 34 and 36 is covered by the plates 50, 50 so that gases cannot pass through. Plates 50 are of sufficient size that openings 54 remain closed both when the boiler is hot and when it is cold. The plates 50, 50, however, are free to slide up and down in the grooves 48 relatively to the plates 34 and 36 so that no stress is put on the superheater elements by the expansion and contraction of the boiler with changes in temperature. The space 55 between a pair of tubes 28 and a set of plates 34, 34a, 36, and 36a may be packed with asbestos or other packing to further insure against leakage of gas through wall 27.

Referring now more particularly to the arrangement of the superheater with respect to the internal baffle 24, I have illustrated in Figs. 5, 6 and 7 a suitable arrangement within my invention for preventing leakage through the baffle. As illustrated, the baffle 24 comprises an intertube section 24a and an interdeck section 25. As appears in Fig. 6, the section 25 may be suspended from metal plates 60, 60 interlocked with the tubes of bank 14 lying alongside the refractory baffle section 24a. However, this feature forms no part of the present invention. As shown, the plates 60 are prevented from sliding on the tube bank 14 by means of clamps 62 and support ribs 64 from which are supported in turn cast metal blocks 63, one face of which carries ribs 68 forming recesses in which is placed refractory material 69. In order to permit the tube ends to pass through the baffle section 25, said section in the arrangement shown is cut away to form a horizontal passage or opening 72. Along the upper and lower edges of the opening 72 in wall 25, means are provided to form grooves 74 and 76 respectively, and similar means (not shown) are provided at the vertical edges of the opening 72 to form vertical grooves. In order to permit the tube ends to pass through the opening 72 without material gas leakage through baffle 24 and without putting stress upon the tube ends, a slideable door or panel 77 is provided for closing opening 72. Panel 77 is formed of blocks 78, 78 which are notched on their vertical edges to receive the tube ends 70 and which are clamped closely to such ends to prevent passage of gas there along. The blocks 78 are rabbed together at their edges to prevent leakage and extend upwardly and downwardly into the grooves 74 and 76. The edges of the grooves 74 and 76 fit the blocks 78 sufficiently close to prevent any material leakage of gas around the edges of the blocks. Blocks 78 are preferably formed with ribs 79 on one face of panel 77 which

hold refractory 80 thereto. In order to further prevent leakage of gas through baffle section 25, ribs 79 may be arranged to follow the contours of the notches for ends 70 and 5 provided with packing grooves 81 (Fig. 7) in the notches for the tube ends 70 to receive asbestos or other packing.

While I have described in detail two arrangements within my invention, it will be 10 understood that the embodiments of my invention shown in the drawings and described above are illustrative only and that I do not limit myself to the details of the foregoing disclosure. In particular, I do no limit 15 myself to superheaters used between the tube backs of a boiler. In fact, my invention is useful wherever a part extends through a baffle or other wall with relative motion between it and the wall in the plane of the 20 baffle or wall.

I claim:

1. The combination with a boiler having a plurality of tube banks, circulator nipples and a vertical wall fixed to said nipples of 25 a superheater intermediate two of said banks, said superheater having headers relative to which the boiler structure moves when changing temperature and having tube ends passing through said wall and arranged in 30 pairs between pairs of nipples, and means for sealing the point at which said ends pass through said wall comprising a plate fixed to a pair of nipples and having an opening for a pair of said tube ends and a plate fixed 35 closely around a pair of tube ends and closing said opening both when the boiler is hot and when it is cold.

2. The combination with a boiler having a plurality of tube banks, circulator nipples 40 and a vertical wall fixed to said nipples, of a superheater intermediate two of said banks, said superheater having headers relative to which the boiler structure moves when changing temperature and having tube ends passing 45 sing through said wall and arranged in pairs between pairs of said nipples, a pair of plates each in two parts meeting along horizontal lines, means for clamping said plates against opposite faces of a pair of adjacent circulator 50 nipples, said plates having openings for a pair of said tube ends, a third plate in two parts meeting along a vertical line and clamped to a pair of said tube ends in position 55 to slide over one of said plates, said third plate covering the opening in one of said first mentioned plates, and means for guiding the vertical edges of said third plate and fixed to the plate over which the third plate is movable.

3. The combination with a boiler having a plurality of tube banks, circulator nipples and a vertical wall fixed to said nipples of a 60 superheater intermediate two of said banks, said superheater having headers relative to which said wall moves when changing tem-

perature and having tube ends passing through said wall, and means for sealing the points at which said ends pass through said wall comprising plates each fixed to a pair of nipples and having openings for said tube 70 ends, and plates fixed closely around said tube ends and closing said openings both when the boiler is hot and when it is cold.

4. The combination with a boiler having a plurality of tube banks, circulator nipples and a vertical wall fixed to said nipples of a superheater intermediate two of said banks, said superheater having headers relative to which the boiler structure moves when changing 75 temperature and having a tube end passing through said wall, and means for sealing the point at which said end passes through said wall comprising a plate fixed to said nipples and having an opening for said tube end and a plate fixed closely around said tube end and closing said opening both when the boiler 80 is hot and when it is cold.

5. The combination with a boiler having a plurality of spaced tube banks including 85 headers and nipples connecting the headers of two of said banks, a superheater intermediate the two of said banks connected by said nipples, closure means fixed to said nipples for closing the spaces therebetween, said superheater having headers relative to which 90 said nipples move when the boiler is changing temperature and having tube ends passing thru said means, and means for sealing the points at which said ends pass thru said closure means comprising plates each fixed to a pair of nipples and having openings for 95 said tube ends, and plates fixed closely around said tube ends and adapted to close said openings both when the boiler is hot and when it is cold.

CHARLES W. GORDON.
